CLAIM

The ornamental design of a male impotence aid, as shown.

DESCRIPTION

FIG. 1 is a top plan view of a male impotence aid showing my new design, the bottom plan view, if it were shown, being identical;

FIG. 2 is an end elevational view of my new design, the opposite end, if it were shown being identical;

FIG. 3 is a side elevational view of my new design, the opposite side, if it were shown, being identical; and,

FIG. 4 is a vertical sectional view, thereof taken on a line corresponding to the line 4—4 in FIG. 1.
